(57) **CLAIM**

The ornamental design for a beverage vessel, as shown and described.

DESCRIPTION

FIG. 1 is a front elevation view of a first embodiment of a beverage vessel showing our new design; the rear being a mirror image thereof;

FIG. 2 is a left side elevation view of the beverage vessel of FIG. 1; the right side being a mirror image thereof;

FIG. 3 is a bottom view of the beverage vessel of FIG. 1;

FIG. 4 is a top view of the beverage vessel of FIG. 1;

FIG. 5 is a front elevation view of a second embodiment of the beverage vessel; the rear being a mirror image thereof;

FIG. 6 is a left side elevation view of the beverage vessel of FIG. 5; the right side being a mirror image thereof;

FIG. 7 is a bottom view of the beverage vessel of FIG. 5; and, FIG. 8 is a top view of the beverage vessel of FIG. 5.

The broken lines illustrate environmental structure and form no part of the claimed design.

1 Claim, 2 Drawing Sheets
